ALARM SIGNAL SYSTEM

John H. Wheelock, Fitzwilliam, N. H., and Hugo F. Cypser, New York, N. Y., assignors to Signal Engineering & Manufacturing Company, New York, N. Y., a corporation of Massachusetts

Application November 7, 1941, Serial No. 418,116

6 Claims. (Cl. 177—360)

The present invention relates to alarm signal systems, particularly fire alarm systems employing a number of bells or other signals adapted to be sounded or otherwise operated in response to the actuation of any one of a number of separate alarm sending stations, such alarm systems being commonly installed in schools, factories, hotels and other large buildings.

In Wheelock Patent No. 2,238,144, issued April 15, 1941, there is shown and described an alarm signal system of the above indicated character, in which the actuation of a sending station is adapted to operate the signals through a number of code sequences determined by the designation of the actuated station. While generally speaking, the signals cease to operate on a code basis after the station has run down, the aforesaid patent also discloses manually operable means at each station for causing operation of the signals on a continuous non-code basis, through functioning of an impulse transmitting device adapted to be energized independently of the station mechanisms.

The present invention relates particularly to a modification of the circuit shown in the aforesaid patent, wherein initial actuation of any sending station automatically closes contacts which have the effect of shunting out the resistor that normally restricts the current traversing the master controller of the system to a supervisory level. Thereafter, successive opening and closing of the coding contacts of the actuated station will serve to transmit a predetermined number of rounds of code sequences, followed by almost immediate functioning of the impulse transmitting device to operate the signals on a continuous basis, irrespective of the fact that the operating mechanism of the actuated station has run down. A further feature of the invention resides in the fact that full power is applied to the winding of the master controller and the several signal circuits under the control thereof, independently of the impulse transmitting device, which does not function in governing the flow of current through the controller winding until after the actuated station has run down and its coding contacts remain closed.

The above and other advantageous features of the invention will hereinafter more fully appear from the following description, considered in connection with the accompanying drawings, in which:

Fig. 1 is a schematic view, illustrating the system in its normal non-operating condition, with

continuous electrical supervision of its various circuits.

Fig. 2 is a schematic view similar to Fig. 1, illustrating the sending of a code impulse of an alarm in response to actuation of one of the sending stations.

Fig. 3 is a schematic view, illustrating the transmission of signals on a continuous non-code basis through functioning of the impulse transmitting device.

Fig. 4 is a fragmentary view, illustrating the construction of a sending station.

Referring first to Fig. 1, the signals 1 which are adapted to be sounded or otherwise electrically operated for giving an alarm, are shown, for purposes of illustration, as being of the single stroke solenoid type, with each providing an operating winding 2 within which moves a magnetic striker 2a. The windings 2 of the signals 1 are adapted to be connected in sections across supply mains 3 and 4, with balancing resistors 5 between the sections, by means of a number of sets of relatively movable contacts 6 and 7 forming part of a master controller, generally designated by the reference character A.

The controller A comprises a winding 8, with a main armature 9 movable in response to energization of the winding to close the several sets of contacts 6 and 7. Normally, the contacts 6 and 7 are open in the position of Fig. 1, even though the winding 8 be traversed by a supervisory current of low amperage, as will hereinafter appear, with full energization of the winding 8 serving to pull in the armature 9 and close the contacts 6 and 7.

The winding 8 of the controller A has one terminal thereof connected to the supply main 4, while the other terminal thereof is connected in series with a number of alarm sending stations S disposed in various locations throughout the system. Each sending station S provides a pair of normally closed coding contacts 10, and these contacts are adapted to be intermittently opened and closed, in accordance with the arrangement 45 of projections 11a on a code wheel 11. Upon actuation of a station S, the code wheel 11 is adapted to be turned through a predetermined number of revolutions by a spring motor 12 of any desired type, such as is usually employed in fire alarm sending stations.

The closed contacts 10 of the several stations S are connected in series with each other and with a controlling resistor 13 by station conductor 14. A return conductor 15 passes through all of the stations, and the conductors 14 and 15 in

each station are adapted to be connected together by a short circuiting switch 16. Normally, the contacts of the switch 16 are open, although each switch 16 is adapted to be closed immediately in response to the actuation of its station, as will later appear.

The several stations S are connected by a conductor 17 to the normally closed contacts 18 of an automatic circuit interrupter 19 of the type shown in Hanel Patent No. 1,968,500, issued July 26, 1932. The interrupter 19 is shown diagrammatically as consisting of a pivoted arm 20 carrying one contact 18, and connected to the free end of a thermal element 21, with the initial tension of the element 21 maintaining the contact 18 on the arm 20 in engagement with the stationary contact 18. Upon the passage of a predetermined current through the thermal element 21, its heating and expansion permits a spring 20a to turn the arm 20 about its pivot to disengage the contacts 18, whereupon current no longer flows through the element 21. The resulting cooling and contraction of the element 21 thereupon causes the arm 20 to reengage the contacts 18, and this cycle is repeated to cause the interrupter to make and break the circuit of the element 21 so long as sufficient current flows through the element to cause its heating and expansion. The fixed end of the thermal element 21 is connected in series with the signal windings 2 and balancing resistors 5 to a current limiting resistor 22, that is in turn connected to the other supply main 3. Normally, a small supervisory current traverses the parts of the system described thus far, as follows:

Beginning at the supply main 3, the supervisory current flows through resistor 22, signal windings 2 and through the thermal element 21 and normally closed contacts 18 of the interrupter 19. The current then traverses the several stations through the conductor 15 and the controlling resistor 13, after which it flows through the coding contacts 10 to the controller winding 8 and other supply main 4. The value of this supervisory current is so low as to have no effect on the main armature 9, although it is sufficient to hold in an auxiliary armature 23, which serves to keep closed a pair of contacts 24, forming part of a control circuit for fault-indicating signals, such as are shown and described in the aforesaid Wheelock Patent No. 2,238,144. Therefore, all parts of the system are in a condition of supervision, ready to indicate the occurrence of a fault, or to transmit a number of rounds of code impulses in response to actuation of a station S, automatically followed by the continuous transmission of impulses on a non-code basis, as will next be described.

Upon actuation of a station S, initial turning of the code wheel 11 by the spring motor 12 causes the coding contacts 10 of the station to be opened, as one contact 10 rides up on the first code projection 11a. Immediately following opening of the contacts 10, the switch 16 is closed by the action of a suitable cam 25, turnable with the code wheel and operating through a lever 26, see Fig. 4. The switch 16 remains closed throughout the operation of the station, and after the station has run down, the switch 16 can be opened only by means of a manually operated reset key, hereinafter described.

The particular mechanism for closing the switch 16 and maintaining it in its closed position forms no part of the present invention, although an illustrative embodiment of one way in which

the switch can be so controlled is shown in Fig. 4. In this arrangement, the cam 25 consists of a ring having a gap at 25a, within which a stud 27 on the lever is disposed in the normal non-operating condition of the station mechanism. Upon turning of the code wheel, an inclined surface of the stud 27 is engaged by a bevelled edge at one side of the gap, to cause the stud to ride up outside the ring to close the contacts 16. Since these contacts 16 are in the form of a knife switch, as shown, the lever 26 will remain in its raised position, even after the station has run down, with the stud 27 remaining in alignment with the gap 25a. In order to open the contacts 16, it is necessary to depress the free end of the lever 26, as by means of a roller 28 carried at the end of an arm 29 pivotally mounted at 30, and adapted to be turned by a reset key. The construction and functioning of the parts of the station mechanism described above are more fully disclosed in the copending application of Ferdinand F. Humphreys, Serial No. 419,097, filed November 14, 1941.

Closure of the contacts 16 of the actuated station, as described above, immediately provides a direct connection between station conductors 14 and 15, so as to shunt out the controlling resistor 13, previously in circuit with the controller winding 8. Consequently, when continued rotation of the code wheel causes the coding contacts 10 to reclose as they pass off a code projection, as shown in dotted lines in Fig. 2, the increased flow of current through the winding 8, due to shunting out of the resistor 13, will cause the main armature 9 to pull in. The resulting closure of the several sets of contacts 6 and 7, also shown in dotted lines in Fig. 2, will establish separate energizing circuits for the signal windings 2, wherein the signal windings are connected directly across the supply mains 3 and 4. Therefore, the first pull in of the armature 9 will result in transmitting the first impulse of the signal code sequence, and subsequent opening and closing of the contacts 10 by the code wheel 11, will transmit the code of the actuated station a predetermined number of rounds, through successive opening and closing of controller contacts 6 and 7.

As the code wheel 11 comes to rest with the contacts 10 closed, to transmit the last impulse of the code sequence, the continued closure of contacts 16, as previously described, causes the controller armature 9 to remain in, due to continued flow of full energizing current through the controller winding 8. With the armature 9 so held in, the upper set of closed contacts 6 and 7, causes the thermal element 21 of the automatic interrupter to be connected directly across the mains 3 and 4, as indicated by the solid arrow heads in Fig. 3. The resulting continued flow of current through the thermal element 21, as contrasted to the discontinuous current flow through the element during the transmission of code impulses, results in heating and expansion of the element after several seconds. The pull of spring 20a on arm 20 thereupon causes the opening of the circuit through the controller winding 8 at the contacts 18, as indicated in dotted lines, whereupon the armature 9 drops out and the controller contacts 6 and 7 open. The cooling and contraction of the thermal element 21, which follows its disconnection from across the line, results in reclosure of the contacts 18, thereby re-establishing the flow of operating current through the controller winding 8. The signals are there-

upon operated again, and obviously subsequent deenergization and reenergization of the controller winding 8 will cause the signals to be automatically operated on a continuous non-code, although intermittent, basis.

As a result of continued closure of the contacts 16 after an actuated station has run down, the signals will operate indefinitely under control of the automatic interrupter. In order to silence the signals and restore the system to the condition of supervision shown in Fig. 1, it is necessary to open the contacts 16 by manually turning the arm 29, as by means of a station test key, so as to move the stud 27 on the lever 26 to its initial position within the gap 25a. Then, subsequent actuation of the station will cause the contacts 16 to be automatically closed, and to function in the manner previously described.

We claim:

1. In an electric signalling system, the combination with transmitting stations each including contacts normally closed in the non-operating condition of the system, and means for repeatedly opening and closing said contacts in accordance with a code sequence, upon the actuation of a station, signals, a device for intermittently transmitting current impulses, a controller having a winding normally in circuit with said station contacts, signals and impulse device, and energizing circuits for said signals and impulse transmitting device, including normally open contacts operable by said controller, of switch means at each station automatically responsive to operation of a station for energizing said controller winding and causing its contacts to either close said signal circuits in accordance with the opening and closing of the coding contacts of the actuated station, without fully energizing said impulse device, or to maintain a circuit for said impulse device, after a station has run down.

2. In an electric signalling system, the combination with transmitting stations each including contacts normally closed in the non-operating condition of the system, and means for repeatedly opening and closing said contacts in accordance with a code sequence, upon the actuation of a station, signals, a thermal operator, a controller having a winding normally in circuit with said station contacts, signals and operator, and energizing circuits for said signals and thermal operator, including normally open contacts operable by said controller, of a switch at each station, automatically closed in response to operation of an actuated station for energizing said controller winding and causing its contacts to close said signal circuits in accordance with the opening and closing of the coding contacts of the actuated station, followed by continuous energization of said thermal operator after the actuated station has run down, for a period sufficient to energize said operator and thereafter cause the intermittent energization of said controller winding to operate said signals without code significance.

3. In an electric signalling system, the combination with transmitting stations each including contacts normally closed in the non-operating condition of the system, and means for repeatedly opening and closing said contacts in accordance with a code sequence, upon the actuation of a station, signals, a thermal operator, a controller having a winding normally in circuit with said station contacts, signals and operator, and energizing circuits for said signals and thermal operator, including normally open contacts operable by said controller, of a switch at each

station automatically closed in response to actuation of a station to energize said controller winding and cause its contacts to close said signal circuits in accordance with the opening and closing of the coding contacts of the actuated station, without fully energizing said thermal operator, said switch means functioning independently of said coding contacts after a station has run down, to fully energize said thermal operator over predetermined periods, and thereby cause the intermittent energization of said controller winding to operate said signals without code significance.

4. In an electric signalling system, the combination with transmitting stations each including contacts normally closed in the non-operating condition of the system, and means for repeatedly opening and closing said contacts in accordance with a code sequence in response to actuation of a station, signals, a resistance between said station contacts and signals, a controller having a winding and a closed supervisory circuit including said station contacts, signals and resistance, and signal energizing circuits, including normally open contacts operable by said controller, with the flow of supervisory current through said controller winding being insufficient to cause closure of its contacts, or to operate said signals, of a device included in said supervisory circuit for intermittently transmitting current impulses, and switch means at each station automatically responsive to operation of an actuated station for removing said resistance from the supervisory circuit to fully energize said controller winding and cause its contacts to close said signal circuits in accordance with the code sequence of the actuated station, said switch means functioning, in the normally closed position of said coding contacts, to energize said impulse transmitting device, and thereby cause the intermittent energization of said controller winding to operate said signals without code significance.

5. In an electric signalling system, the combination with transmitting stations each including contacts normally closed in the non-operating condition of the system, and means for repeatedly opening and closing said contacts in accordance with a code sequence in response to actuation of a station, signals, a resistance between said station contacts and signals, a controller having a winding and a closed supervisory circuit including said station contacts, signals and resistance, and signal energizing circuits, including normally open contacts operable by said controller, with the flow of supervisory current through said controller winding being insufficient to cause closure of its contacts, or to operate said signals, of a device included in said supervisory circuit for intermittently transmitting current impulses, and switch means at each station automatically responsive to operation of an actuated station for removing said resistance from the supervisory circuit to fully energize said controller winding and cause its contacts to close said signal circuits in accordance with the code sequence of the actuated station, without fully energizing said impulse transmitting device, said switch means functioning independently of said coding contacts after the actuated station has run down, to fully energize said impulse transmitting device and thereafter cause the intermittent energization of said controller winding, to operate said signals without code significance.

6. In an electric signalling system, the combination with transmitting stations each including contacts normally closed in the non-operating condition of the system, and means for repeatedly opening and closing said contacts in accordance with a code sequence, upon the actuation of a station, signals, a resistance between said station contacts and signals, a controller having a winding normally in circuit with said station contacts, signals and resistance, and signal energizing circuits including normally open contacts operable by said controller, of a device for intermittently transmitting current impulses normally in circuit with said winding, station contacts and signals, and switch means auto-

15

matically responsive to operation of an actuated station for shunting out said resistance to fully energize said controller winding and cause its contacts to close said signal circuits in accordance with opening and closing of the coding contacts of the actuated station, until after the latter has run down, said switch means thereafter functioning during continued closure of said coding contacts to energize said impulse transmitting device, and thereby cause the intermittent energization of said controller winding to operate said signals without code significance.
